DESIGN FOR A PARKING METER CASING OR SIMILAR ARTICLE

John F. Lindberg, Chicago, Ill.

Application August 13, 1938, Serial No. 79,304

Term of patent 14 years

To all whom it may concern:

Be it known that I, John F. Lindberg, a citizen of the United States and a resident of the city of Chicago, in the county of Cook and State of Illinois, have invented a new, original, and ornamental Design for a Parking Meter Casing or Similar Article, of which the following is a specification, reference being had to the accompanying drawing, forming a part thereof.

On the drawing:

Figure 1 is a front elevational view of the parking meter casing showing my new design.

Figure 2 is a top plan view thereof.

The numerals appearing in Figure 1 are merely illustrative.

I claim:

The ornamental design for a parking meter casing or similar article, as shown and described.

JOHN F. LINDBERG,
